CLAIM

The ornamental design for a crochet plant shaped auto air freshener, as shown and described.

DESCRIPTION

FIG. 1 is an exploded, top-perspective view showing my new design of a crochet plant shaped auto air freshener with the diffuser bottle removed for ease of illustration.

FIG. 2 is a second perspective view of the new design in another configuration, shown in its environment hanging from a rearview mirror;

FIG. 3 is a front view thereof with the environment removed for ease of illustration;

FIG. 4 is a back view thereof;

FIG. 5 is a right side view thereof;

FIG. 6 is a left side view thereof;

FIG. 7 is an enlarged top view thereof;

FIG. 8 is an enlarged bottom view thereof;

FIG. 9 is an enlarged bottom perspective view thereof; and,

FIG. 10 is an enlarged front view of the removable diffuser bottle by itself for ease of illustration.

The broken lines depict portions of the article that form no part of the claimed design. The broken lines showing a rearview mirror in FIG. 2 are for the purpose of illustrating environmental structure and form no part of the claimed design.
